MOBILE COMBINATION MOTOR-GENERATOR,
AIR COMPRESSOR, HEATER, BLOWER, AND
WATER PUMP

Stanley A. Holtkamp, Centralia, Ill., assignor to Holtkamp Co., Centralia, Ill., a corporation of Delaware

Filed Dec. 5, 1968, Ser. No. 14,797

Term of patent 14 years

Int. Cl. D12—10

U.S. Cl. D14—3

Fig. 5.

FIG. 1 is a front elevational view of a mobile combination motor-generator, air compressor, heater, blower, and water pump, showing my new design:

FIG. 2 is a rear elevational view thereof:

FIG. 3 is a left side elevational view thereof:

FIG. 4 is a right side elevational view thereof; and

FIG. 5 is a top plan view thereof.

I claim:

The ornamental design for a mobile combination motor-generator, air compressor, heater, blower, and water pump, substantially as shown.
